UNITED STATES PATENT OFFICE.

WILLIAM H. BURNETT, OF MOUND CITY, MISSOURI.

BOTTLE-CAP REMOVER.

1,267,052.

Specification of Letters Patent. Patented May 21, 1918.

Application filed December 3, 1914. Serial No. 875,256.

To all whom it may concern:

Be it known that I, WILLIAM H. BURNETT, a citizen of the United States, residing at Mound City, in the county of Holt and 5 State of Missouri, have invented certain new and useful Improvements in Bottle-Cap Removers, of which the following is a specification.

My invention relates to a bottle cap re- 10 mover.

The invention aims to provide a novel construction of article of this nature which can be preferably stamped from sheet metal in a single piece and subsequently bent, and 15 to provide an article of this kind which has an attaching hook arm to engage a belt, a bottle cap-receiving opening, a bottle cap engaging nose and means in the form of one or more cloth-piercing projections at the 20 said opening by means of which the article may be fastened to trousers against accidental displacement.

With the foregoing and additional objects which will later appear, in view, the invention 25 has been embodied in preferred form in the device illustrated in accompanying drawings and hereinafter described.

In said drawings,

Figure 1 is a front elevation of the im- 30 proved article.

Fig. 2 is a side elevation of the improved article and

Fig. 3 is a side elevation of the improved article shown in connection with a co-operating belt, key-ring, and portion of trousers, the latter being shown in section.

Referring specifically to the drawings, wherein like reference characters designate like or similar parts, a bottle cap-opening 40 section or arm is shown at 1, it being enlarged at its lower end as at 2 and being provided with a bottle cap-receiving opening 3. At the upper extremity of the opening is provided a bottle cap-lifting nose 45 member 4 and projecting into the said opening 3 and beyond the rear wall of the section 1, as best seen in Figs. 2 and 3, are cloth engaging or piercing spurs 5.

Slightly spaced from the front face of 50 section 1, connected thereto and extending downwardly from its top is a resilient hook arm designated 6. Extending upwardly

from the arm 6 and slightly spaced therefrom is a resilient article supporting hook arm 7.

It will be realized that the parts described comprise an integral structure or an article which is made in a single piece and further that the production of the nose 4 and spurs 5 may occur simultaneously with the cutting 60 and removal of the blank to provide the opening 3.

The article is designed to be fastened to a belt as seen at 8, to support a key-ring as seen at 9 and to engage trousers shown frag- 65 mientarily as at 10 so as to prevent displacement of the article both vertically and horizontally.

In use, the article is applied or hung on a belt by passing the hook arm 6 over the belt. 70 After this hooking occurs, the spurs 5 may be engaged with the trousers. It will be realized that the article is fastened by the spurs 5 and hook 6 against accidental dis- placement. The key-ring 9 is passed over 75 the hook arm 7 and into the space intermediate the arm 7 and the arm 6. Arm 7 at its top is preferably closer to the arm 6 than at its bottom, so as to more securely support the ring 9 against displacement. When used 80 to remove a bottle cap the section 1, and arms 6 and 7 are grasped as a handle and the nose 4 is applied to the cap or the spurs 5 applied to the cap and then the article is worked as a lever in the usual manner. The 85 two spaced lugs or spurs 5 serve to minimize the danger of lateral movement of the article relatively to the bottle cap in the operation of removing the cap.

As merely the preferred embodiment of 90 the invention has been illustrated and described, it is to be understood that changes in the details of construction may be resorted to within the spirit and scope of the invention.

I claim:

In a device of the class described having a bottle cap removing section, said section being provided with an opening to receive the bottle cap, said opening being provided 100 with a plurality of spurs formed integral with said section, on its inner surface, extending at an angle to the plane of said cap removing section adapted to engage the cap,

and provide independent lateral movement of the device in the action of removing the cap, a resilient supporting hook member having a resilient supporting arm formed therewith, adapted to suspend the device on a garment, said spurs, by reason of their being formed at an angle to the plane of said cap removing section, being adapted

to prevent the accidental disengagement of the hook from the garment. 10

In testimony whereof I affix my signature in presence of two witnesses.

WILLIAM H: BURNETT.
